UNITED STATES PATENT OFFICE.

CHARLES H. REPATH AND FRANK E. MARCY, OF ANACONDA, MONTANA.

ROASTING-FURNACE.

SPECIFICATION forming part of Letters Patent No. 740,589, dated October 6, 1903.

Application filed November 22, 1902. Serial No. 132,431. (No model.)

To all whom it may concern:

Be it known that we, CHARLES H. REPATH and FRANK E. MARCY, citizens of the United States, residing at Anaconda, in the county 5 of Deerlodge and State of Montana, have invented certain new and useful Improvements in Roasting-Furnaces, of which the following is a full, clear, and exact description, reference being had to the accompanying drawings, forming a part hereof.

Our invention has relation to improvements in roasting-furnaces; and it consists in the novel arrangement and combination of parts more fully set forth in the specification and 15 pointed out in the claims.

In the drawings, Figure 1 is a middle vertical section of the furnace. Fig. 2 is a transverse section taken in a plane above the bottom of the second hearth on the line 2 2 of 20 Fig. 1. Fig. 3 is a top plan of the furnace. Fig. 4 is an enlarged sectional detail showing the stub-arm on the rotating shaft. Fig. 5 is an elevational detail of the same, and Fig. 6 is a sectional detail showing the calcine-spout 25 and special plow.

The object of our invention is to construct a combined reverberatory and turret furnace, the composite structure serving to combine the advantages of both types, while at the 30 same time it eliminates their disadvantages. In the ordinary type of turret or McDougall furnace there are enormous losses due to flue-dust, a result which is inevitable from the very nature of the furnace. The material 35 drops through a series of hearths, encountering ascending currents of hot blast, the latter causing the fine particles to be over-roasted and carried away in a fine dust or powder, thereby causing great losses of valuable material. On the other hand, while the 40 reverberatory roaster and the reverberatory matte-furnace make but little dust they are expensive to run, both as to labor and fuel.

Our present invention eliminates both of 45 the aforesaid objections, requiring, too, a minimum amount of repairs, entailing a minimum amount of labor and attention, and materially reducing the operating expenses.

While the present improvements are preferably used in connection with the water-cooled McDougall furnace, it is to be under-

stood that we do not limit their application thereto, as they may be used on turret-furnaces generally. Where, however, the improvements are made a part of a water-cooled 55 turret-furnace provided with removable stirring-teeth, the composite furnace thus produced results not only in an economy of space and fuel, but prevents loss of heat, and loss from flue-dust, utilizing as fuel the sulfur 60 contained in the sulfur-bearing ores, prevents overroasting of the fine particles, admitting atmospheric oxygen directly with the hot gases, preventing overheating of the stirrers, and providing for the ready removal of the 65 latter and other parts liable to be worn, without having to wait until the furnace cools.

In detail the invention may be described as follows:

Referring to the drawings, F represents the 70 furnace, the same being provided with a series of superposed hearths 1 2 3 4 5 6, (the number may be varied,) through the center of which passes the vertically-disposed hollow water-cooled stirring-shaft 7. The shaft 75 is provided with a series of pairs of hollow radial arms 8, extending over the several hearths. In Fig. 1 the arms on alternate hearths are hidden from view, as they extend directly back of the shaft in the position 80 shown. The rake or stirrer teeth 9 are preferably removable. Throughout the hollow shaft extends a water-pipe 10, provided with open-ended distributing-pipes 11, extending through each of the stirring-arms 8. The 85 material is fed into the uppermost hearth 1 through the hopper H and by the action of the stirring-arms is carried toward the center, where it drops through upon the second hearth. At first the material is separated 90 from the main body of the hearth-chambers by the annular shield 12, but is soon plowed out by the rake 13, which is fastened to the stub-arm 14. The arms 14, as shown in the drawings, are carried by the shaft 7 and disposed intermediate the bases of each pair of arms 8 over every hearth discharging from its margin or outer edge. The material continues on its outward course, caused by the stirring-arms 8, and rakes 9, when it reaches 95 the outer edge of the hearth where it drops to the third hearth through the several chutes 100.

15 where again it is fed to the center of the furnace, and so on throughout the several hearths until it is delivered into the discharge-hopper C.

5 In the majority of the particulars referred to and in details shown in the drawings and not herein specifically mentioned or alluded to the present furnace conforms to a class well known and covered by Letters Patent, 10 and while our improvements are preferably applied to furnaces equipped as shown they may be applied to any furnace of the McDougall or turret type.

Referring now particularly to our improvements, as the material becomes heated and burns the gases are led over it and to the hearths above through the peripheral chambers D, said chambers spanning vertically two consecutive hearths, as best seen in Fig. 20, and being disposed on opposite sides of the furnace. The gases pass over the bridge or wall 16, taking an upward course through the opening 17 and impinging against the dome-shaped or arched roof of the next hearth above, 25 whence they are deflected upon the charge in said hearth like in a reverberatory furnace. The gases thus pass on from hearth to hearth, as indicated, through the chambers D, the gases being always on top of the 30 material and never blown through it. This method causes a minimum amount of flue-dust, produces an even roast, and results in a great economy of heat, (the sulfur in the charge contributing to the supply of fuel.) 35 To always keep the gases in this path and to stop the gases from taking the opposite route of the material, interchangeable shields 12 are placed in the center of the hearths 2, 4, and 6, said shields surrounding and overlapping 40 the lower projecting edges of the rings 18, located around the center openings 19 from the hearths above. These shields collectively form a complete cylinder, which can be put in place from the doors of the furnace by a 45 special pair of tongs (not shown) which are hooked into the lugs 20. Then the shield is slipped between the lugs 21 22 of the stirring-arms, then over the stub-arm 14 in the same way. The remaining three shields are put in 50 place in the same way and all four firmly held by the two keys 23, passed through the extensions 14' of the stub-arms. The gases are kept from taking the opposite route of the material on the outside of the hearths 3 55 and 5 by the stationary spouts or chutes 15, which have inclosed sides and reach within a few inches from a line which coincides substantially with the bottom of the plows or rakes. This spout has the effect of keeping 60 the gases out; yet the material comes down and is carried away by the special plow 24, Fig. 6. The top of this spout is located by a door 25, so, if necessary, it can be cleaned out or replaced with a new one. If desired, 65 this spout can be placed within the brick

casing instead of projecting into the hearth-chamber.

To keep the material from ever falling down alongside the vertical rotating shaft 7, it will be noticed that the ring 26 (located between hearths 2 3 and 4 5, respectively) projects above the material on the hearth, and at the same time there is a flange 27, that extends out over the ring 26. The doors 28 are used to clean or repair the chambers D, at the same time affording a means of admitting the required amount of atmospheric oxygen.

We may of course qualify the present construction in minor details without in any wise affecting the nature or spirit of our invention.

By disposing the chambers D on opposite sides of the furnace the gases of course take the most available route (see arrows, Fig. 1) to insure the best results in the matter of roasting, saving of fuel, &c.

Having described our invention, what we claim is—

1. In a furnace having a plurality of vertically-disposed hearths, peripheral chambers establishing communication between the several hearths, a central vertical stirring-shaft in said hearths, a series of stirring-arms radiating from said shaft and extending into the several hearths, spouts or chutes leading from and extending a suitable distance beyond the margins of an alternate series of hearths to the series immediately beneath for permitting the descent of the material, yet excluding the gases, and special rakes carried by the stirring-arms for removing the material delivered through the spouts, substantially as set forth.

2. In a furnace having a plurality of hearths, a rotatable shaft passing through the hearths, a series of arms radiating from said shaft and extending into the several hearths, the alternate hearths of said series having central openings for the discharge of the material into the hearths beneath, and annular shields carried by the shaft adjacent to said openings, to confine the course of the gases in their proper upward direction through the furnace, substantially as set forth.

3. In a furnace having a series of hearths, a central rotatable shaft, a stub-arm on said shaft, a rake carried by said stub-arm, the said rake serving to remove the material fed from the hearth above through an opening surrounding the shaft, substantially as set forth.

4. In a furnace having a series of hearths, a central rotatable shaft passing through the hearths, a series of arms radiating from said shaft and entering the several hearths, lugs formed at the bases of the arms, stub-arms disposed on the shaft between the arms, a series of sectional shields adapted to be inserted between the lugs and be supported on the stub-arms, and keys for locking the sections, the latter forming a complete ring or cylin-

der when assembled, said cylinder occupying a position immediately below the discharge-opening surrounding the shaft and leading from the hearth above, substantially as set forth.

5. In a furnace having a plurality of hearths, a series discharging from the center into the remaining hearths, and the latter discharging from their outer margins into the former, and spouts leading and projecting a suitable distance into the centrally-discharging series from the hearths feeding into them, substantially as set forth.

6. In a furnace, a rotatable shaft, a series 15 of stirring-arms carrying teeth or rakes, radiating from said shaft, and stub-arms having teeth, located between the radiating arms, substantially as set forth.

7. A roasting-furnace having superposed 20 hearths apertured for the passage of the ore, and means for crowding the ore toward the apertures, in combination with stationary spouts extending between the hearths and

adapted to direct the ore on its way from one hearth to the next hearth below in such a 25 manner as to protect the ore from the influence of the draft, substantially as set forth.

8. A roasting-furnace comprising superposed hearths apertured alternately at the center and at the periphery, means located 30 between the shelves for crowding the material alternately inward to the central apertures and outward to the peripheral apertures, and stationary spouts located between the hearths and arranged to direct the ore on its 35 way from one hearth to the next hearth below in such manner as to protect the ore from the influence of the draft, substantially as set forth.

In testimony whereof we affix our signatures in presence of two witnesses.
